(57) **CLAIM**

The ornamental design for a mobile computing device as shown and described.

DESCRIPTION

FIG. 1 is a first perspective view of a mobile computing device;

FIG. 2 is a second perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The broken lines shown in the drawings illustrate environment and portions of the mobile computing device that form no part of the claimed design.

1 Claim, 6 Drawing Sheets
